LOCK

Norman B. Hurd, New Britain, Conn., assignor
to The American Hardware Corporation, New
Britain, Conn., a corporation of Connecticut

Application April 3, 1929, Serial No. 352,114

5 Claims. (Cl. 70—91)

This invention relates to locks and in particular to a lock adapted to be easily disassembled to have its combination changed or a new lock casing having a different combination substituted.

5 An object of the invention is to provide a lock incorporated with a knob and shank which may be quickly disassembled by the introduction of a special key within the usual key slot in a plug.

10 It is another object of the invention to provide a special interlocking or interengaging member movable to engaged and disengaged position by rotation of the plug to hold the knob and shank together or permit their separation, this interlocking member being operated by a special
15 key.

In certain places, such as office buildings and hotels, where tenants are constantly changing and where it is desired to have different keys for opening individual rooms, it is convenient to have means whereby the locks can be changed so that a different key will be required to open it. The present invention relates to such devices in which the lock may be operated in the usual manner by a key, and, by means of a special
20 key, the lock may be disassembled so that a new casing requiring a different key may be substituted.

25 A feature of importance is that the shank and knob members of the lock structure are provided with interengaging portions, one interengaging or interlocking portion carried directly by the shank and preferably comprising small annular inside segmental recesses. The other interengaging member is preferably in the form of a sleeve having segmental arcuate lugs at the rear of the knob adapted to fit within the segmental recesses within the shank. The sleeve is rotatably mounted upon but secured against axial movement relative to the key plug in the lock casing. The means for connecting and disconnecting the knob and shank are therefore exceedingly simple, and do not add materially to the weight, size or cost of manufacture of the construction. The construction also is such that the entire knob may be easily detached and lock casings may be quickly removed and others substituted by a workman unskilled in lock making.

30 With the above and other objects in view, my invention includes the features of construction and operation set forth in the following specification and illustrated in the accompanying drawing.

35 In the accompanying drawing annexed hereto and forming a part of this specification I have shown my invention embodied in a lock of the

pin tumbler type mounted within a hollow knob, but it will be understood that the invention can be otherwise embodied and that the drawing is not to be construed as defining or limiting the scope of the invention, the claims appended to this specification being relied upon for that purpose.

40 In the drawing—

Fig. 1 is a longitudinal view partly in section of lock mechanism, the members of which are shown in operative relation to each other;

Fig. 2 is a longitudinal view similar to Fig. 1 but showing the principal members of the lock disassembled and separated;

Fig. 3 is a perspective view of parts of the lock widely separated.

45 In the above-mentioned drawing I have shown but one embodiment of the invention which is now deemed preferable, but it is to be understood that changes and modifications may be made within the scope of the appended claims without departing from the spirit of the invention.

50 Referring more in detail to the figures of the drawing, I show a lock comprising a shank member in the form of a hollow spindle 5 adapted to be secured to a door or other member and usually employed as a knob spindle to actuate the usual latch. Through this shank extends longitudinally the square spindle 6 usually operated by a key for operating the lock or latch mechanism, or both, associated with the lock. As such lock and latch mechanism forms no part of the present invention, reference to its construction will be omitted.

55 Adapted to be mounted on the spindle 5 and disengageably held in position thereon is a knob 7. Within this knob is mounted the lock mechanism which is of the well known pin tumbler type. This mechanism comprises a lock casing 8 having a plurality of pin tumblers 9 of the usual type operated by a suitable key which fits in a plug 10 in the usual manner. Special means are provided for disengaging the knob from the shank so that the knob with the lock casing may be readily removed from the shank. In this separated condition a new lock casing and plug may be inserted requiring a different key to operate it.

60 In order to connect and disconnect the knob 7 from the spindle 5, a sleeve 12 is rotatably mounted on the key plug 10 and at the rear of the knob. Axially extending clutch lugs 13, shown clearly in Figs. 2 and 3, are provided on this sleeve 12 so that in one position they engage within recesses 14 in the end of the spindle 5.

separated by axially extending clutch lugs, and in another rotative position of the sleeve 12 they are disengaged from the recesses 14 and permit removal of the sleeve with the knob from the shank. The spindle 6 is connected to the plug 10 or an extension thereon and may be removable with said plug.

Fig. 1 shows the method of operating the lock in the usual manner. It will be noted that the ordinary or pass key 15 inserted within the plug is not long enough to affect the tumbler 16 in the innermost recess. This tumbler and its driver 17, it will be noted, pass through the plug and sleeve so that in the position of the driver 17 shown in Fig. 1 the sleeve is prevented from rotating relative to the lock casing. The plug, however, is free to turn in the usual manner. These positions of the tumbler 16 and driver 17 are maintained so long as the knob and hollow spindle 5 are locked together by the lugs 13 engaging within the recesses. In order to lift the innermost tumbler so that the sleeve will be free to rotate relative to the lock casing and compelled to rotate with the plug a special key 18 is required, shown in Fig. 2. The effect of this key, as will be seen from this figure, is to lift the innermost tumbler 16 sufficiently so that the sleeve 12 and plug are locked together, whereupon the sleeve is free to be rotated relatively to the lock casing 8. The special key shown in Fig. 2 is bitted similarly to that shown in Fig. 1 so that it will properly operate the remaining tumblers of the lock. When this special key 18 is inserted rotation of the plug and the tumbler 16 will rotate the sleeve to disengage the lugs from their recesses so that the lock may be disassembled as shown in Fig. 2.

Fig. 3 shows the preferred form of the recesses on the shank 5 and the lugs 13 on the sleeve. As will be seen, the recesses 14 are cut into inner surfaces of forwardly extending projections 19-19 diametrically opposed to each other. The lugs 13 are formed on the outer surface of the sleeve 12 designed to fit within the projections. As the recesses and lugs extend over less than an arc of 90° the sleeve may be locked or unlocked relative to the shank by rotating the sleeve approximately 90°.

In the form shown, the shank 5 and knob 7 have longitudinally engageable portions for preventing relative rotation of these parts; that is to say, the projections 19-19 on the shank 5 engage between complementary projections 20-20 preferably integrally carried by the knob 7. Thus, when the projections 19 are fitted in the recesses between the projections 20-20, the knob and shank turn together, and when the lugs 13 on the sleeve 12 are positioned so as to lie within the recesses 14-14, the knob and shank are securely locked together against relative longitudinal movement.

In the particular form shown, the projections 20-20 are provided with recesses 21-21 for the reception of the lugs 13 when the latter are turned out of the recesses 14-14 in the shank. It will be seen that when the lugs 13-13 are engaged within the recesses 21 of the knob, the lock casing 8 will be held within the knob against axial displacement. After the knob has been removed from the shank, the sleeve 12 may be rotated by the special key 18 so as to withdraw the lugs 13 from the recesses 21, after which the lock mechanism 8 may be withdrawn rearwardly from the knob. When the lock casing is removed, the tumblers may be reset so as to provide a different

combination and then replaced or a new cylinder or other lock mechanism having a different combination may replace the old one just withdrawn. The parts may then be reassembled in the inverse order of disassembly as described.

I claim:

1. In a device of the character indicated, a knob supporting hollow spindle, a knob, said knob and spindle having integral interfitting axially extending lugs to prevent relative rotation of said knob and spindle, said lugs being provided with internal annular grooves registering with each other, said knob having an opening at the rear to receive a lock mechanism, a lock mechanism in said knob and key operable means associated with said lock mechanism and including an annular interrupted lug means to be received in the annular registering grooves in the lugs on said spindle and knob for locking said knob and spindle together.

2. In a device of the character indicated, a knob supporting shank, a knob, said knob and shank having integral interfitting axially extending lugs to prevent relative rotation of said knob and shank, said knob having an opening at its rear for the insertion and removal of a lock mechanism including a rotatable key plug in said casing, a member for securing the lugs on said shank and knob together, means for positively locking said member to said lock case, said means being key operable to positively lock said member to said plug and unlock the same from said lock casing, whereby said member may be key moved through the medium of said plug for locking and unlocking said lugs on said knob and shank.

3. In a device of the character indicated, a knob, a knob supporting hollow spindle, said knob and spindle having integral interfitting axially extending clutch shoulders to prevent when engaged independent rotation of said parts, key actuated mechanism insertible and removable from said knob at the rear thereof including a key plug extending rearwardly beyond the knob, with clutch interlocking means mounted on and rotatable by said plug to interconnect said clutch members to prevent axial separation of said parts, a key operable tumbler normally operating to prevent rotation of said plug, another tumbler normally operating to positively hold said interlocking means in clutch locking position while leaving the plug free to turn therein, said tumbler being displaceable by a key to free it from clutch locking position and connect it to said plug for rotation thereby to free said clutch members.

4. In a device of the character described, a knob, a knob supporting hollow spindle, said knob and spindle having integral interfitting axially extending clutch members to prevent independent rotation of said knob relatively to said spindle, key controlled lock mechanism, said knob also having an opening at its rear to permit the insertion and removal of said lock mechanism, said lock mechanism including a rotatable plug, tumbler mechanism therefor, clutch interlocking means mounted on said plug and rotatable thereby to interconnect said clutch members to prevent axial separation of the knob from the spindle when said plug is rotated by one key, said plug being rotatable by a different key independently of said clutch interconnecting means.

5. In a latch of the character described, a hollow spindle, a knob, axially extending intercon-

necting clutch members to prevent independent rotation of the knob relatively to said spindle, a key plug mounted in said knob and projecting rearwardly therefrom into said spindle, means mounted on said plug and rotatable thereby when locked thereto to interconnect the clutch members to prevent longitudinal separation of the knob from the spindle, key controlled mecha-

nism operable by one key to lock said interconnecting means to said plug to cause it to turn with the plug to engage and disengage said clutch members, said key controlled mechanism being operable by a different key to permit the rotation of the plug independently of the clutch interconnecting means.
